UNITED STATES PATENT OFFICE.

OTTO W. SCHAUM, OF PHILADELPHIA, PENNSYLVANIA.

HYDRO-EXTRACTOR.

SPECIFICATION forming part of Letters Patent No. 552,550, dated January 7, 1896.

Application filed July 1, 1892. Serial No. 438,668. (No model.)

To all whom it may concern:

Be it known that I, OTTO W. SCHAUM, of the city and county of Philadelphia, State of Pennsylvania, have invented a certain new and useful Improvement in Hydro-Extractors, of which the following is a true and exact description, reference being had to the accompanying drawings, which form a part of this specification.

My invention relates to hydro-extractors of the same general character as that described in the patent to W. P. Uhlinger, granted August 22, 1876, and numbered 181,500, my present invention having for its object to provide improved means for suspending the entire apparatus so as to obviate or minimize the vibrations communicated from the machine to the floor or foundation upon which it is situated. This result I accomplish by suspending the tub upon a series of slightly-diverging links or rods which are made adjustable.

The nature of my invention will be best understood as described in connection with the drawings in which it is illustrated, and in which—

Figure 1 is an elevation of the improved hydro-extractor taken on the section-line 1 2 of Fig. 2. Fig. 2 is a plan view taken on the section-line 3 4 of Fig. 1. Fig. 3 is an elevation showing a cleaning-door in the tub, and Fig. 4 a section on line 5 6 of Fig. 2.

A represents the tub having a bottom flange A² reinforced, as indicated at A', where the pivots of the suspending-rods are connected with it. A cavity of spherical outline, as indicated at a, is formed in each of these reinforcements A'.

B B, &c., indicate a series of standards having projecting heads B', in the top of which are formed cavities of spherical outline, as indicated at b.

C and D are rods provided at one end with heads of spherical form, which heads are indicated at C' and D', and fit respectively into sockets b and a, forming a ball-and-socket joint, as indicated. The other ends of the rods C and D are provided with screw-threads running in opposite direction, and the two rods are connected by a turnbuckle E, also having right and left threads, and which engage the threaded ends of rods C and D. This con-

struction enables me to adjust the length of the suspended rods made up in the way described readily and conveniently, and obviates the necessity of having any projection screwed on above the top of the standards.

It will be noticed that the suspending-rods are set at slightly-diverging angles. This I have found to be a feature of material advantage, for, while it permits a sufficient freedom of motion to take up undue jar, it prevents an undue swinging of the tub.

Another feature of my invention is the opening A⁵ formed through the seat of the tub A and provided with a door L, which is secured in place by bolts l l, and to which I prefer to secure the upper part l' of a spout l' a' leading from a drain-passage A⁴ in the tub. The opening A⁵ gives me access to the outside of 70 the basket G, and enables me to keep it clean without removing it from the tub.

The remaining features of my device shown consist of the shaft F stepped in a projection A⁸ at the bottom of the tub and to which is secured the perforated basket G. The upper part of the shaft is supported by the end of a bracket H secured to the edge of the tub, as shown, and which supports also the engine indicated at I, the connecting-rod K of which communicates motion to the shaft of a crank-disk J.

Having now described my invention, what I claim as new, and desire to secure by Letters Patent, is—

1. In a hydro-extractor the combination with a tub A of a series of swing rods set at diverging angles adapted to support the tub, supports for said rods and means for adjusting them longitudinally, substantially as and for the purpose specified.

2. In a hydro extractor the combination with a tub A with a series of threaded rods D D secured to the tub by ball and socket joints, a series of rods C C threaded in opposite direction to rods D, a series of turn-buckles E uniting the rods D C, standards B and ball and socket joints uniting rods C with the standards.

3. In a hydro-extractor the combination with a tub A with a series of threaded rods D D secured to the tub by ball and socket joints, a series of rods C C threaded in opposite direction to rods D, a series of turn-buckles E unit-

ing the rods D. C. standards B and ball and socket joints uniting rods C with the standards and set at greater distance from the center of the tub than the joints uniting rods D 5 with the tub.

4. In a hydro-extractor the combination with a tub A having a drain passage and an opening A⁵ formed in the side of the tub substantially over the drain passage, of a door L 10 arranged to close said opening.
5. In a hydro-extractor the combination

with a tub A having a drain opening A⁴ and an opening A⁵ formed in the side of the tub substantially over the drain passage, of a door L arranged to close said passage and having 15 a flange l' which forms the cover of the drain passage.

OTTO W. SCHAUER.
